UNITED STATES PATENT OFFICE.

WILLIAM BITTNER, OF BROOKLYN, NEW YORK.

SHEET-METAL-BENDING MACHINE.

Application filed December 30, 1927. Serial No. 243,574.

My invention relates to a machine used for the purpose of bending the edges of thin sheet metal. In the sheet metal trade, it is necessary to make a great many joints, and 5 to do this the edges of the metal must be bent substantially at right angles to the main body portion of the sheet, and so far as I am aware there is no machine that will do this work, in one operation.

10 In my Patent 1,613,307, issued January 4th, 1927, I have shown and described a machine which will do the work in two operations, and after considerable study of the problem and many experiments, I have discovered 15 means of bending the edge of the metal substantially at right angles to the rest of the sheet in one pass of the metal through the machine; and it is therefore the principal object of my invention to provide a machine 20 which will accomplish this purpose, thereby saving a tremendous lot of time in the forming of the edges of the sheet metal. Another object of my invention is to provide a device which will do this work, that is relatively 25 simple and inexpensive in first cost, and upkeep.

Another object of my invention is to provide a machine which may be readily replaced in whole, or in part by a new apparatus or 30 parts thereof.

These and other objects will be apparent to one skilled in the art of sheet metal working after a study of the specification taken in connection with the annexed drawing, wherein, 35 Figure 1 is a plan view of the top of the machine, showing the cover of the bending device per se in open position.

Figure 2 is a side elevation of the complete machine, showing the driving motor 40 and the driving motor coupling the switch and connecting gear mechanism.

Figure 3 is a view on a reduced scale, but larger than that shown in Figures 1 and 2, of the unitary structure which is used in bending the metal.

Figure 4 is a plan view of the bending rolls and an auxilliary bending device, used with the bending rolls.

Figure 5 is a part sectional view substantially full size through the unitary bending structure, with certain parts removed, those shown being substantially full size.

Figure 6 is an enlarged view of the auxilliary forming device used with the rolls, the view being an elevation looking at Figure 4 55 from the bottom of the sheet toward the top.

Figure 7 is a perspective view of the top end of Figure 6 turned at 180 degrees.

Figure 8 is an end view of a piece of sheet metal coming from the machine, while 60

Figure 9 is a plan view showing how the edge is rolled up to the position shown in Figure 8.

Referring now to the details wherein like numbers refer to corresponding parts in the various views: 1 is a stand preferably made of structural steel, having a substantially flat top 2 of any suitable material, such as cast iron. Mounted on the bottom of the top 2 is an electric motor 3, operated by a switch or controller 4. The motor shaft, by means of a coupling 5, is connected to a pair of worm gears housed within the housing 6. From the gear case 6 extends a shaft 7 upwardly through the table top 2. 75

The important part of my machine resides in the unitary structure mounted on the top of the table. This comprises a housing 8 preferably having a cover or lid 9, hinged to the housing 8, in any suitable manner, as by 80 pivot bolt 10 which passes through lugs on both the housing and the cover, which keeps foreign material from getting in between the gears and also preventing the operator from accidentally getting caught in the gears. 85

The bottom side of the housing 8 is machined off to provide a seat 11, which fits on the top 2, and is held thereto by a pair of bolts 12. Adjacent the seat 11, the housing is machined out at 13, to provide a space or 90 seat for the forming roll 14, the seat 13 having sufficient depth, so that the face of the forming roll 14, is slightly below the seat 11 of the housing, so that the roll does not engage the stand top 2. The roll 14 preferably 95 has a hub 15, extending through the wall of the housing 16, and fitting snugly therein so as to act as a guide and support for the forming roller 14. The hub 15 has a keyway 17, to key the hub 15 to the driving shaft 7, on the upper end of which is keyed a driving gear 18. A nut 19 on the end of the shaft 7 is used to hold the gear 18 in position. It will be noted from Figure 3 that the inner

surface of the wall of the housing is machined at 20 to provide a free running space for the gear 18.

Adjacent the cut away portion 13, which is provided for the forming roll 14, the bottom of the housing, represented by the line 21 is cut away at an angle, and positioned substantially at right angles to this annular portion 21 there is mounted through the wall 16 of the housing, a stub shaft 22, on the outer end of which is carried a forming roller 23, and within the housing a gear 24 is keyed to the stub shaft and held in position thereon by a nut 25. The stub shaft is carried in a bearing bushing 26, preferably made of a good quality of brass or bronze. The bushing 26 is preferably in the form shown in Figure 4, and against the flat face 27, there is positioned the plate 28 preferably of steel, which is engaged by an adjusting screw 29, carried in a bushing 30, supported in the wall of the housing. After the adjusting screw 29 has been set as hereinafter explained, it is locked in position by a set screw 39 (see Figure 3). To the outer end of the adjusting screw 29, is fastened an adjusting member 31, on which is carried an indicator 32, calibrated at 33 to indicate the thickness of the sheet metal to be passed between the forming roll. After the indicator 32 has been set to the proper point, as will be hereinafter described it is locked in place by a set screw 34. On account of the stub shaft 22 and its gear 24, and forming roll 23 being set at an angle the two gears 18 and 24 are tapered to accommodate this position of mounting of the stub shaft. As will be noted from Figures 3 and 5, the forming roll 23 has a tapered knurled peripheral edge, the knurling being provided for the purpose of gripping the metal so as to draw it between the two rolls 14 and 23.

I have found this setting of the stub shaft on the forming roller 23 to be necessary in order to bend the edge of the metal at right angles, and as a further essential feature, I have found it necessary to use a forming device, which comprises a stud 35 made of a suitable grade of steel, which may be positioned in the top 2, as shown in Figures 3 and 5. From Figure 4, it will be seen that the forming device 35 is positioned to one side of the central line joining the two rolls 14 and 23, and has an end especially formed and projecting between the peripheral edges of the roller. One side of this specially shaped end is arcuately cut at 36 to substantially the same arc as the forming roller 14, and as shown in Figure 4, has a clearance from the edge of the roll 14, of approximately five thousandths of an inch. The other side 37 of said projecting end is peculiarly formed in a manner which I have determined by experiment to be the best for holding the edge of the sheet metal in such a position as to start it curving as indi-

cated in Figures 8 and 9, and as the roll 23 due to its knurled surface drags the metal through between the rolls 14 and 23, the forming device just indicated starts the bending operation and holds the metal in such a position that the rolls perform the rest of the work.

As has been indicated the stub shaft 22, its gear 24 and forming roll 23 may be adjusted bodily in a lateral direction by the adjusting mechanism described, and by means of the gauge 32, the rolls may be set with respect to each other to accommodate various thicknesses of metal within a given range, for a given size of the unitary device. As will be seen from Figures 3 and 5, the forming roll 23, is positioned in a different plane from the forming roll 14 and there is a clearance below the face of the forming roll 23 for the sheet of metal being operated on, to pass beneath the forming roll and housing.

While I have shown the forming device 35 as mounted in the table top 2, it may be positioned in the wall 16 of the housing 8. When mounted as in Figure 5, in the stand top 2 it may be put in by a pressed fit so that it will not shift in position, but in order to remove it for fitting in a new one, the stud 38 is provided for forcing the forming device 35 out of the top 2.

I have found that my object is obtained, that is to say, the edge of the metal is bent at right angles, when the stub shaft 22 and its associated forming roll 23, are set at an angle of approximately seven and one half degrees and when so set, I prefer to divide the taper on the two gears 18 and 24 evenly, it being understood that the teeth on these gears are of sufficient depth to allow for the lateral displacement of the stub shaft and its parts to accommodate various gauges of sheet metal. In the device shown this will form sheet metal up to approximately forty thousandths of an inch thick; and for heavier gauges the parts of course, are proportionately enlarged, or changed to meet the condition of thicker metal, or an edge wider than that which is to be formed in the particular device shown, and described herein. All of these changes and others indicate that the details may be varied over considerable range, without departing from the spirit of the invention and the scope of the appended claims.

Having thus described my invention, what I claim is:

1. In a sheet metal bending machine, at least two rolls spaced apart, means for driving said rolls, means associated with at least one of said rolls for drawing a sheet of metal so that a portion passes between said rolls, and a forming device positioned between the peripheries of said rolls and to one side of the line joining their centers, said forming device extending so as to intersect the planes of said

rolls and having a face contour which functioning with the rolls, turns the edge of the metal to the desired angle.

2. In a sheet metal bending machine,

- 5 at least two rolls, spaced apart, means for driving said rolls, means associated with at least one of said rolls for drawing a sheet of metal so a portion passes between said rolls, means for adjusting at least one of said rolls with respect to the other to accommodate sheets of varying thickness and a forming device positioned between the peripheries of said rolls and to one side of the line joining their centers, said forming device extending so as to intersect the planes of said rolls and having a face contour which functioning with the rolls, turns the edge of the metal to the desired angle.
- 10
- 15
- 20
- 25
- 30
- 35
- 40
- 45
- 50

3. In a sheet metal bending machine, at

- least two rolls spaced apart, and having their axes set at an angle to each other, means for driving said rolls, means for quickly adjusting the distance between said axes to operate on sheets of varying thickness, means associated with the adjustable roll for drawing a sheet of metal so a portion passes between said rolls and a forming device positioned between the peripheries of said rolls and to one side of the line joining their centers, said forming device extending so as to intersect the planes of said rolls and having a face contour which functioning with the rolls, turns the edge of the metal to the desired angle.

4. In a sheet metal bending machine,

- 35 a driving shaft having a gear and roll thereon, a stub shaft having a gear in mesh with the gear on the driving shaft and a roll adjacent the first roll, said stub shaft being set at an angle with respect to the drive shaft, whereby the plane of the roll thereon is at an angle to the plane of the roll on the driving shaft, said stub shaft with its gear and roll being bodily adjustable laterally with respect to the driving shaft, its gear and roll, means associated with one of said rolls for driving sheet metal therebetween, and a forming device positioned between the peripheries of said rolls but offset from a straight line joining the centers of said rolls and cooperating with said rolls to turn the edge of the metal substantially at right angles to the rest of the sheet.
- 40
- 45
- 50

5. In a sheet metal bending machine, a

- 55 driving shaft having a gear and roll thereon a stub shaft having a gear in mesh with the gear on the driving shaft and a roll adjacent the first roll, said stub shaft being set at an angle with respect to the drive shaft, said roll on the stub shaft being somewhat elevated above the first roll and having its plane at an angle to the plane of the first roll and having means for drawing metal between it and the first roll, means for shifting the stub shaft with its gear and roll laterally with respect to the driving shaft for the purpose de-
- 60
- 65

scribed, and a device having a specially formed end extending between said rolls and cooperating with them to turn the edge of the metal to the desired angle.

6. A machine for bending the edge of thin metal comprising a stand having a flat top and carrying a suitable driving means below said top, a unitary structure rigidly mounted on the upper part of said top, said unitary structure consisting of a box having a readily removable cover, and having a seat on its bottom side, at one end to fit on said stand top and a cut away portion adjacent said seat and a further portion cut at an angle to the first cut away portion, a roll positioned in the first cut away portion, a driving shaft extending from said driving means to the interior of said box, a gear within the box and rotated by the driving shaft, a stub shaft carried by that part of the box having the portion cut at an angle, and having a gear thereon within the box driven by the first gear and a roll positioned adjacent said angular cut part of the box and close to the first mentioned roll, and a forming device positioned between said rolls and cooperating therewith to turn the edge of the metal as it is drawn by the rolls beneath said box.

7. A unitary structure for bending the edge of thin metal consisting of a box like housing having a portion of one side finished to form a seat for fastening it to a support said housing having a cut away portion adjacent said seat, a forming roll positioned in said cut away portion adjacent said seat, said forming roll adapted to be driven by a suitable driving means, a gear wheel within the housing operated by said driving means, a stub shaft carried by said housing, a gear wheel on the stub shaft within the housing and adapted to be driven by the first gear wheel, a forming roll on the stub shaft and positioned exterior of the housing adjacent the first roll but in a different plane and having clearance between its outer face and the support for the purpose described, and a forming device having a special shaped end positioned between said forming rolls to guide and assist in turning the edge of the metal substantially as described, as the edge passes between the rolls.

8. A unitary structure for bending the edge of thin metal consisting of a box like housing having a portion of one side finished to form a seat, a support to receive said seat, said housing having a cut away portion adjacent said seat, a forming roll positioned in said cut away portion, a suitable driving means for driving said roll, a gear wheel within the housing operated by said driving means, a stub shaft carried by said housing, a gear wheel on the stub shaft within the housing and adapted to be driven by the first gear wheel, a forming roll on the stub shaft and positioned exterior of the housing ad-

adjacent the first roll but in a different plane and having clearance between its outer face and the support for the purpose described, means for quickly adjusting the distance between

6 said forming rolls to receive material of varying thickness, means associated with at least one of said rolls for drawing the material between them, and a forming device having a special shaped end positioned between 10 said forming rolls to guide and assist in turning the edge of the metal substantially as described as the edge passes between the rolls.

9. A unitary structure for bending the 15 edge of thin metal consisting of a box like housing having a portion of one side finished to form a seat, a support to receive said seat, said housing having a cut away portion adjacent said seat, a forming roll positioned in 20 said cut away portion, a suitable driving means for driving said roll, a gear wheel within the housing operated by said driving means, and a stub shaft carried by said housing, a gear wheel on the stub shaft within the 25 housing and adapted to be driven by the first gear wheel, a forming roll on the stub shaft and positioned exterior of the housing adjacent the first roll but in a different plane and having clearance between its outer face 30 and the support for the purpose described, manually operable means extending without the housing for shifting laterally said stub shaft with its gear and roll for the purpose described, said latter roll having its peripheral edge knurled to draw the material between the rolls, and a forming device having 35 a special shaped end positioned between said forming rolls to guide and assist in turning the edge of the metal substantially as described, as the edge passes between the rolls.

10. A unitary structure for bending the edge of thin metal consisting of a boxlike housing having a portion of one side finished to form a seat, a support to receive said seat, 45 said housing having a cut away portion adjacent said seat, a forming roll positioned in said cut away portion, a suitable driving means for driving said roll, a gear wheel within the housing operated by said driving means, a stub shaft carried by said housing at a small angle diverging outwardly from the axis of said gear wheel and roll, a gear 50 wheel on the stub shaft within the housing, both said gear wheels being slightly tapered to properly mesh on account of said angular setting of said stub shaft, a forming roll on the stub shaft and positioned exterior of the housing adjacent the first roll and having clearance between its outer face and the support 55 for the purpose described, means for quickly shifting laterally the stub shaft its gear and roll, said latter roll having its peripheral edge tapered toward the housing and knurled for the purposes described and 60 a forming device having a special shaped end

positioned between said forming rolls to guide and assist in turning the edge of the metal substantially as described, as the edge passes between the rolls.

11. A unitary structure for bending the 70 edge of thin metal consisting of a boxlike housing having a portion of one side finished to form a seat, a support to receive said seat, a gear wheel and a forming roll positioned, the gear within the housing and the roll without, a driving shaft to operate both the gear wheel and the roll, a stub shaft carrying a gear wheel within the housing in mesh with the first gear and a forming roll without the housing to co-operate with the first 80 roll, said stub shaft being set at a small angle to said driving shaft and laterally adjustable with respect thereto, said housing being cut away so the roll on the stub shaft is clear from the support to allow the material to be bent to pass thereunder, said last mentioned roll having a tapered knurled edge for the purposes described, and a forming device having a special shaped end positioned between said forming rolls to guide and assist in turning the edge of the metal 85 substantially as described as the edge passes between the rolls.

12. A unitary structure for bending the edge of thin metal consisting of a box like 90 housing having a portion of one side finished to form a seat, a support to receive said seat, a driving gear and a driven gear within the housing, a pair of forming rolls positioned outside said housing and associated one each with each of said gear wheels, a driving shaft for operating one of said gears and its associated roll, a stub shaft carrying the other gear wheel and its associated roll, said last mentioned roll being in a different 100 plane than the other roll and having a tapered knurled edge for the purposes described, and a forming device having a special shaped end positioned between said forming rolls to guide and assist in turning the edge of the metal substantially as described as the edge passes between the rolls.

13. A unitary structure for bending the edge of sheet metal comprising a housing, a feed table, at least a driving and a driven gear within the housing, a driving member to operate the driving gear, a forming roll operated by the driving member, a second forming roll operated through the medium of the driven gear, said forming rolls being disposed outside the housing and in different planes, the second roll being spaced away from the feed table so the stock may pass beneath the roll, and a forming device co-operating with said rolls to guide the stock 115 and assist in turning the edge.

14. A unitary structure for bending the edge of sheet metal comprising a housing, a feed table, at least a driving and a driven gear within the housing, a driving member 120

to operate the driving gear, a forming roll operated by the driving member, a second forming roll operated through the medium of the driven gear, said forming rolls being disposed outside the housing and in different planes, the second roll being spaced away from the feed table, so the stock may pass beneath the roll, and having a tapered

knurled edge to draw the stock between the rolls, means for adjusting the space between the forming rolls and a forming device co-operating with said rolls to guide the stock and assist in turning the edge. 10

In testimony whereof, I affix my signature.

WILLIAM BITTNER.
